UNITED STATES PATENT OFFICE.

JESSE A. B. SMITH, OF GLENBROOK, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,280,886.

Specification of Letters Patent.

Patented Oct. 8, 1918.

Application filed February 5, 1917. Serial No. 146,557.

To all whom it may concern:

Be it known that I, JESSE A. B. SMITH, a citizen of the United States, residing in Glenbrook, in the county of Fairfield and State of Connecticut, have invented certain new and useful Improvements in Type-Writing Machines, of which the following is a specification.

My invention relates to typewriting machines, and is herein disclosed as applied to an Underwood typewriting machine, having a fan-fold attachment, such as is disclosed in the patent to Wernery & Smith, 1,132,055. In such machines, a single long sheet or web 15 of paper, which is folded lengthwise one or several times, is fed from the rear of the machine around beneath the typewriter platen, and up in front past a knife which is adapted to tear off sections of the sheet 20 or web at a suitable distance above the printing line.

In said fan-fold machines, the relationship of parts is usually such as to enable as great a part as possible of the work of handling the sheets to be done in a practically 25 automatic or mechanical manner. One of these features includes an arm formed as an extension of the paper table having thereon a stop or gage against which the typist may 30 mechanically adjust the fan-fold sheets so that they may be torn off at the proper point. In doing this, the platen is usually swung up clear of the usual feed roll, and the paper table is pulled over toward the 35 typist, who pulls the work-sheets forward until the leading edge thereof strikes said gage. The typist then throws the platen back to normal position, where it holds the work-sheets against the feed roll, and then 40 tears off the advanced sheets by the knife which lies along the end of the form printed on the sheet. Then the platen may be caused to advance the work-sheet.

Since the fan-fold web is an integral 45 sheet, all the forms thereon must be of the same size, and this sometimes renders the bookkeeping system unnecessarily bulky or easily deranged, owing to the fact that the separated forms are likely to be misplaced. 50 Moreover, all the sheets of the fan-fold web are of the same color, to avoid prohibitive cost, and it is desirable to have some record sheets of a kind of paper which is distinct

in color from the fan-fold record. A separate or distinctive record sheet is usually 55 made as a carbon copy; the first or ribbon-made copy being usually a bill to be sent to the customer.

An object of my invention is to keep this record web separate, and to enable it to be 60 separately fed along, and for this purpose I provide means whereby it is held or guided separately from the fan-fold web. This separate sheet may have the typed carbon copies of a succession of the forms of which 65 the fan-fold web is made up; and may serve the purpose of a record or condensed-record copy.

I provide means whereby a special record sheet may be fed through the machine to 70 together with the fan-fold web, and between the latter and the platen, and may be also separately held and retained in a stationary condition while the fan-fold web is being advanced for the purpose of bringing a new 75 section of said sheet into writing position.

To enable this record sheet to clear the 76 page, which serves to position the fan-fold web for cutting, said record sheet, as it advances from the platen, may be carried behind the usual paper table. I have provided 80 said table with a slot or opening which may direct said record sheet away from the fan-fold web. This separation is facilitated because the record sheet is usually of comparatively thin paper, and lies against the paper table, while the fan-fold sheets form a rather 85 stiff web, and so fail to enter said slot.

In order to align the record sheet when first inserted, the paper table may be provided with alining devices; and said table may also be slotted or perforated opposite or adjacent said devices to enable the typist to see that the record sheet is in proper position when said table is in inverted position, 95 at which time the record sheet lies under the paper table.

The alining devices may be in the form of 100 fingers or rolls, and they may also serve to clip and hold said record sheet temporarily stationary when the platen is lifted up and the web is being pulled forward to bring a form into printing position. Said record sheet may be gaged by the aforesaid fingers or rolls. The rolls or clips may automatically become ineffective when writing is 105

being done on the work-sheet, that is to say, when the platen is returned to printing position. Certain features of the invention are useful for controlling separate sheets in other positions than between the remaining work-sheets and the platen.

Other features and advantages will hereinafter appear.

In the accompanying drawings,

10. Figure 1 is a perspective view showing so much of a fan-fold Underwood machine as serves to illustrate my invention as applied thereto.

Fig. 2 is a sectional side view of the same, 15 showing the parts in writing position.

Fig. 3 is a similar view, showing the parts when the handle on the typewriter carriage has been released, to enable the platen to swing upward.

20. Fig. 4 is a diagrammatical sectional view, showing the relationship of the parts, and illustrates the fan-fold web cut off and the record sheet intact.

Fig. 5 is a view showing the platen and 25 the measuring elements thrown forward in the act of measuring before cutting the fan-fold web.

Fig. 6 is a view of a section of one form of record sheet.

30. Fig. 7 is a perspective view of a record sheet perforated and adapted to be torn into sections like Fig. 6.

In the Underwood fan-fold typewriting machine, the typewriter carriage 1 travels 35 on a rear rail 2 being fed forward in the usual manner at every stroke of a type-bar 3. Fast to the typewriter carriage and traveling therewith is a rearwardly-extending frame 4, which includes a supporting roll 4^a running on a rail 5^a. Said frame includes parallel rails 5 and 6 for a carbon sheet-carrier 7, and also includes a rear cross-bar 8, over which the fan-fold sheets or web and the record sheet may be pulled to be 45 advanced forwardly under a platen 9. In order to permit the sheets to be pulled forward easily in this manner and to enable the carbon sheets to be advanced with them, and the latter to be pulled back independently thereof, the platen 9 is journaled in the usual fan-fold swing frame 10, which is pivoted on a front bar 11 of the usual typewriter carriage 1. Said frame is usually latched down by means of a pair of hooks 12, 55 one at each side of the machine, which engage pins 13 on said frame, said hooks being fast on a rock shaft 14 journaled in the typewriter carriage.

In order to release the swing frame 10, the 60 hooks 12 may be swung rearwardly, as seen in Fig. 3, to ineffective position, one of the hooks being provided with an extension 15, forming a finger-piece for so releasing them. When so released, the swinging frame may 65 be swung forward until the paper table 16

thereof is substantially in a horizontal position, as seen in Fig. 5. In this position, the fan-fold web 17 may be easily drawn forward under the platen, it being alined by the usual side gages, not shown herein. At 70 the same time, a record sheet 18 may be threaded forward between the platen and the fan-fold web 17. In drawing forward the web, there are threaded between its folds two or more carbon sheets 19 and 20, according to the number of copies to be made in the fan-fold web, and there is also threaded between the record sheet and the fan-fold web a carbon sheet 21. These carbon sheets are caught in holders 22 in the manner usual 75 in these fan-fold machines, said holders forming part of a light carriage 23, which travels on the rails 5 and 6, and is adapted to seize the carbon sheets and to feed them forward and backward between the folds 85 of the fan-fold sheet or web when it is in the horizontal position seen in Fig. 5, in which position there is so little friction between the carbon sheets and the folded web that the sheets may be easily pulled rearwardly by 90 means of the carriage 23.

To enable the typist to operate the carriage 23 conveniently, it is provided with a forwardly-extending handle 24. In threading the fan-fold sheet and the record sheet 95 beneath the platen in the manner described, it is frequently customary merely to advance the web sheets and carbon sheets far enough to enable the feed rolls to grip them when the platen is swung back to normal writing 100 position (see Fig. 2). If it be desired to accurately posititon the record sheet at this time, the record sheet may be advanced until it strikes a pair of gages 25, of which there is one at each side of the paper table 16, which 105 gages may be in the form of rolls. The carbon sheets may be similarly positioned by allowing them to be drawn forward with their carriage 23 until said carriage strikes a stop, such as the cross-bar 26^a, which arrests them 110 in the right position.

The paper table may include side gages for the sidewise positioning of the record sheet. In order to enable the typist to see that the record sheet is accurately positioned 115 and not accidentally caught against a wrong part, the paper table is provided with slots 27 at each side thereof adjacent the gages 25, and extending partly thereunder, through which the typist may see the record sheet beneath the paper table 16 in its inverted position, seen in Fig. 5.

In the ordinary working of the fan-fold machines, the fan-fold web is, as mentioned above, usually advanced to the point at which 125 it will be seized by the platen when the platen comes down against the usual releasable feed rolls 28 and 29. This is just about the point seen in Fig. 5, viz., the point beneath the platen when the platen is in its up- 130

per position. The carbon sheets are in the meantime positioned by the friction of the carbon sheets because the carriage 23 is light enough to allow friction to bring the carbon sheets to nearly the same position. Then the platen is thrown back to writing position, in which position it is held by the hooks 12, which are cammed rearwardly as the swing frame approaches the writing position, because the pins 13, which are provided with follower rollers 30, strike the front cam faces 31 of the hooks 12.

As soon as the swing frame is fully seated in writing position, the hooks 12 are swung forward to effective position by the spring 32. This swinging forward of the hooks causes them to remove the rolls or clips 25 to the ineffective position, seen in Fig. 2. To effect this, there is provided on one of the hooks 12 a follower pin 33, which is adapted to lift the rolls 25 by riding over a rearwardly-extending arm 34 fast on the shaft 35, said shaft having also fast thereon arms 36 on which the rolls 25 are mounted. The rolls 25 are thrown to effective position just as soon as the handle 15 is moved rearwardly, because this carries the follower pin 33 to ineffective position, and thereby permits the spring 37, coiled around the shaft 35, to throw the rolls 25 to effective position.

When the platen 9 is against the feed rolls 28 and 29 the usual line-space handle 38 may be actuated to rotate the platen and thereby advance the fan-fold web 17, the record sheet 18 and the carbon sheets 19, 20 and 21, the deflector plate 38* having been thrown back by its handle 39* to guide the sheets around the platen (see Fig. 4). The sheet then may be written on and filled in in the usual manner. The advancing of the record sheet 18, by the line-space operation, causes it to catch under and pass behind the turned-up lip 39, forming part of the upper end of the paper table 16, thus carrying the record sheet through the opening formed by said lip and behind said paper table, while the fan-fold web 17 is too bulky and too stiff to catch under the lip 39, and passes up over an extension arm 40 of said table. The record sheet passes behind the lip 39, because it is thin and lies directly flat against the face of the paper table 16.

After the form on the fan-fold web has been filled in, the handle 15 may be swung rearwardly to release the swing frame 10; then said frame may be drawn forward by the typist, who seizes the extension 40, swinging the frame down to the horizontal inverted position seen in Fig. 5. In this position, the rolls or clips 25 hold the record sheet 18 against advancing. While the sheet 18 is thus held stationary, the typist pushes the handle 24 rearwardly, carrying all the carbon sheets (including the sheet which

contacts with 18) substantially back to a point beneath the platen, and at the same time pulls the fan-fold web 17 along until it strikes the usual adjustable fan-fold gage 41, all as shown in Fig. 5. This indicates to the typist that that sheet is in position for being torn off. The typist is enabled to measure in this way by the gage, because the record sheet has been carried out of the way of the gage by the lip 39, mentioned above. The typist now swings the swing frame 10 back to writing position, Fig. 4, and tears off the fan-fold web by the knife 43, which is formed on the edge of the plate 38^a. This sequence of operations makes the typewritten items on the record sheet follow each other closely, although they may be widely spaced on the fan-fold web. This follows from the fact that the record sheet does not move when the fan-fold sheet is pulled forwardly with the platen in its elevated position. Thus, the invention may be utilized for condensed billing, where the bills are on the fan-fold sheet.

The typist then is ready to fill in a new 90 form and may advance the platen by means of the line-space handle 38 to bring the proper line of the form to the printing point.

For some purposes, it may be desired to have the record sheet in the form of separable sheets of any desired size suitable for putting in books, and the sheets may, therefore, be in the form of a rolled web 44, provided with suitable perforations 45, marking off sections to fit the binding books, and by which the sections may be torn off, the web also being provided with openings 46 to fit in the post of the binders of the books. These openings may be brought to proper position relatively to the lines of writing on the sheets of the roll 44 by alining the end sheet against the gages 25. 95 100 105

The slot 29^b is conveniently of exactly the width of the record sheet intended to be used in the machine, so that the ends 47 of 116 the slot 39^b form convenient side gages for the record sheet 18. This record sheet is advantageously wider than the width of the folded fan-fold web, so that although the rollers 25 engage the record sheet, they are 115 always clear of the fan-fold web, because they lie outside of the edges thereof.

Variations may be resorted to within the scope of the invention, and portions of the improvements may be used without others. 120

Having thus described my invention, I claim:

1. In a typewriting machine, the combination of a platen, feed rolls beneath said platen, and a paper-table adapted to receive the leading edge of a sheet above said platen, an opening being provided in said table to guide the sheet nearest the platen clear of the other sheets. 125

tion of a platen, feed rolls beneath said platen, a paper-table adapted to receive the leading edge of a sheet above said platen, an opening being provided in said table to 5 guide the sheet nearest the platen clear of the other sheets, and a lip extending above the table from said opening adapted to catch said sheet.

3. In a typewriting machine, the combination with a revoluble platen, of feed rolls beneath said platen, a paper-table adapted to receive the leading edges of work-sheets fed around said platen, an end gage for the work-sheets, and means for conducting the 10 work-sheet nearest the platen out of the way of said gage.

4. In a typewriting machine, the combination with a revoluble platen, of feed rolls beneath said platen, a paper-table adapted 20 to receive the leading edges of work-sheets fed around said platen, an end gage for the work-sheets, means for conducting the work-sheet nearest the platen out of the way of said gage, and holding means for said work-sheet separate from the work-sheets brought 25 against the gage.

5. In a typewriting machine, the combination with a revoluble platen, of feed rolls beneath said platen, a paper-table adapted 30 to receive the leading edges of work-sheets fed around said platen, an end gage for the work-sheets, means for conducting the work-sheet nearest the platen out of the way of said gage, holding means for said work-sheet 35 separate from the work-sheets brought against the gage, and a knife adapted to tear off the gaged work-sheets above the printing line.

6. The combination with a carriage and a 40 swing frame including a revoluble platen forming part of said carriage, of a paper-table, means for holding a work-sheet on said table, and means for automatically making said holding means ineffective when the 45 platen is in its normal position.

7. The combination with a carriage, of a swing frame including a revoluble platen and a paper-table, means for holding a work-sheet to said paper-table, and means for automatically making said holding means ineffective when the table is swung to its normal position, said means, however, becoming effective when the table is swung to an abnormal position.

8. In a typewriting machine, the combination with a carriage and a swing frame including a revoluble platen, of a paper-table swingable to inverted position with said frame to bring a work-sheet beneath the 50 table, and means for holding the work-sheet on said table when the table is swung to inverted position.

9. In a typewriting machine, the combination with a carriage and a swing frame including a revoluble platen, of a paper-table

swingable to inverted position with said frame to bring a work-sheet beneath the table, and means for holding the work-sheet on said table when the table is swung to inverted position, said table being provided 70 with openings to enable the operative to inspect the adjustment of the work-sheet while the table is in its inverted position.

10. In a typewriting machine, the combination with a carriage and a swing frame including a revoluble platen, of a paper-table swingable to inverted position with said frame to bring a work-sheet beneath the table, means for holding the work-sheet on said table when the table is swung to inverted position, said table being provided 75 with openings to enable the operative to inspect the adjustment of the work-sheet while the table is in its inverted position, and an end gage for said work-sheet adjacent said 80 openings.

11. In a typewriting machine, the combination with a carriage and a swing frame including a revoluble platen, of a paper-table swingable to inverted position with said 90 frame to bring a work-sheet beneath the table, means for holding the work-sheet on said table when the table is swung to inverted position, said table being provided with openings to enable the operative to inspect the adjustment of the work-sheet while the table is in its inverted position, an end gage for said work-sheet adjacent said 95 openings, and a separate end gage adapted to cooperate with other work-sheets.

12. In typewriting machine, the combination with a carriage including a table, a swing frame and feed rolls separate from said frame, of a platen forming part of said frame and adapted to receive the leading 100 edge of a work-sheet above said platen, and a clip device moving with said frame adapted to hold work-sheets to said table when the table is swung from normal position, but ineffective when the platen is in normal position.

13. In a typewriting machine, the combination with a carriage and feed rolls forming part of said carriage, of a swing frame in said carriage comprising a platen normally lying against said feed rolls, a table also forming part of said frame and adapted to receive work-sheets fed around said platen, normally ineffective means for holding a work-sheet against said table, and 115 means whereby said holding means becomes effective when the platen is swung in its frame away from said feed rolls.

14. In a typewriting machine, the combination with a carriage and feed rolls forming part of said carriage, of a swing frame in said carriage comprising a platen normally lying against said feed rolls, a table also forming part of said frame adapted to receive work-sheets fed around said platen, 120

normally ineffective holding means for holding a work-sheet against said table, and means whereby said holding means become effective when the platen is swung in its frame away from the feed rolls.

15. In a typewriting machine, the combination with a carriage, of a swing frame forming part of said carriage, latches for normally holding said swing frame in its 10 normal position, holding devices for holding a sheet on said swing frame but normally held ineffective by said latches, and means for making said holding devices effective by moving said latches to ineffective position.

16. In a typewriting machine, the combination with a carriage, of a swing frame forming part of said carriage, latches for normally holding said swing frame in its normal position, holding devices for holding a sheet on said swing frame but normally held ineffective by said latches, means for making said holding devices effective by moving said latches to ineffective position, said holding devices adapted to serve as 20 end gages, and separate end gages for separately positioning another work-sheet.

17. In a typewriting machine, the combination with a carriage and a swing frame therein, of a revoluble platen in said swing 30 frame, feed rolls against which the platen can be swung by swinging said frame, a gage for the work-sheet nearest the platen, and a separate gage for the remaining work-sheets.

18. In a typewriting machine, the combination with a carriage and a work-table adapted to receive the leading edge of a work-sheet, of a device for holding said sheet against the table, a swing frame in 40 which said table and device are mounted, a latch for holding said swing frame in its normal position, a handle for releasing said latch, a rock arm on which said device is mounted, and a cam fast to said rock arm 45 adapted to release said feed roll when the latch is in effective position and to become ineffective when the latch moves to rearward ineffective position.

19. In a typewriting machine, the combination with a carriage, and a work-table adapted to receive the leading edge of a work-sheet, of a device for holding said sheet against the table, a swing frame in which 50 said table and device are mounted, a latch for holding said swing frame in its normal position, a handle for releasing said latch, a rock arm on which said device is mounted, a cam fast to said rock arm adapted to release said device when the latch is in effective 55 position and to become ineffective when the latch moves to rearward ineffective position, a second sheet-holding device, a common shaft on which said devices are mounted, a second latch, and a common shaft on which 60 said latches are mounted.

20. In a typewriting machine, the combination with a revoluble platen and a swing frame in which it is mounted, of feed rolls for holding a work-sheet against the platen when in normal position, and away 70 from which the platen may be swung by said swing frame, a gage for adjusting the work-sheet nearest the platen, a separate gage for adjusting the outside work-sheet, a carbon paper-carrier, and a gage for positioning the carbon paper-carrier to position the carbon paper relatively to the printing point.

21. In a typewriting machine, the combination with a revoluble platen, of means 80 for rotating said platen to advance work-sheets past the printing point, a gage for the outside work-sheets, a knife adjacent the printing point by which the outside sheets may be cut off at the point determined by the gage, and a separate holding device for the inside work-sheet adapted to hold the inside work-sheet while the outside work-sheets are being cut off by the knife.

22. In a typewriting machine, the combination with a revoluble platen, of means for rotating said platen to advance work-sheets past the printing point, a gage for the outside work-sheets, a knife adjacent the printing point by which the outside sheets 95 may be cut off at the point determined by the gage, a separate holding device for the inside work-sheet adapted to hold the inside work-sheet while the outside work-sheets are being cut off by the knife, a paper table over which the work-sheets are 100 fed, and means whereby said table guides the inside work-sheet clear of the outside work-sheets.

23. In a typewriting machine, the combination with a revoluble platen, of means for rotating said platen to advance work-sheets past the printing point, a gage for the outside work-sheets, a knife adjacent the printing point by which the outside sheets 105 may be cut off at the point determined by the gage, a separate holding device for the inside work-sheet adapted to hold the inside work-sheet while the outside work-sheets are being cut off by the knife, a paper-table over which the work-sheets are 110 fed, and means whereby said table guides the inside work-sheet clear of the outside work-sheets, and carries it behind the table.

24. In a typewriting machine, the combination with a revoluble platen, of means for rotating said platen to advance work-sheets past the printing point, a gage for the outside work-sheets, a knife adjacent the printing point by which the outside 115 sheets may be cut off at the point determined by the gage, and a separate holding device for the inside work-sheet adapted to hold the inside work-sheet while the outside work-sheets are being cut off by the knife, 120

- said holding device being normally ineffective.
25. In a typewriting machine, the combination with a revoluble platen, of a paper-table, a shiftable gage forming part of an extension of said table, a knife adapted to cut off work-sheets at a point measured by said gage, said table having an opening adapted to cause a work-sheet to pass behind said table, edges forming part of said opening and acting as edge guides for said last-named work-sheet, holding devices for said last-named work-sheet, and standing clear of narrow work-sheets, separate holding devices for all the work-sheets, and a carbon paper-carrier adapted to shift carbon paper into and out of the bite between the platen and certain of said holding devices.
- 10 26. In a typewriting machine, the combination with a revoluble platen, of a paper-table, a shiftable gage forming part of an extension of said table, a knife adapted to cut off work-sheets at a point measured by said gage, said table having an opening adapted to cause a work-sheet to pass behind said table, edges forming part of said opening and acting as edge guides for said last-named work-sheet, holding devices for 15 said last-named work-sheet, and standing clear of narrow work-sheets, separate holding devices for all the work-sheets, a carbon paper-carrier adapted to shift carbon paper into and out of the bite between the 20 platen and certain of said holding devices, a swing frame of which said platen and certain of said holding devices form a part, latches holding said swing frame in position, a handle for releasing said latches, and 25 connections whereby operation of said handle causes certain of said holding devices to become effective.
27. In a typewriting machine, the combination with a revoluble platen, of a paper-table, a shiftable gage forming part of an extension of said table, a knife adapted to cut off work-sheets at a point measured by said gage, said table having an opening to cause a work-sheet to pass behind said table, edges forming part of said opening and acting as edge guides for said last-named work-sheet, holding devices for said last-named work-sheet, and standing clear of narrow work-sheets, separate holding devices 30 for all the work-sheets, a carbon paper-carrier adapted to shift carbon paper into and out of the bite between the platen and certain of said holding devices, and separate means for releasing the separate holding devices.
- 35 28. The combination with means for shifting interleaved carbons backwardly along a fan-fold web, of a platen over which the web feeds in a tortuous course, said platen being 35 displaceable to straighten out the web, to permit the backward shifting of the carbons interleaved between the plies of the web, and means connected to said carbon-shifting means for shifting a carbon arranged between the fan-fold web and an exterior sheet.
- 40 29. The combination with means for shifting interleaved carbons backwardly along a fan-fold web, of a platen over which the web feeds in a tortuous course, said platen being 40 displaceable to straighten out the web, to permit the backward shifting of the carbons interleaved between the plies of the web, and means connected to said carbon-shifting means for shifting a carbon arranged between the fan-fold web and an exterior sheet disposed between the fan-fold web and the platen.
- 45 30. The combination with means for shifting interleaved carbons backwardly along a fan-fold web, of a platen over which the web feeds in a tortuous course, said platen being 45 displaceable to straighten out the web, to permit the backward shifting of the carbons interleaved between the plies of the web, and means for retaining stationary in the machine during the successive advances of the fan-fold web an additional work-sheet or web, to lie between the fan-fold web and the platen, to receive a condensed record of 50 the entries typed upon a succession of forms on the fan-fold web.
- 50 31. The combination with means for shifting interleaved carbon backwardly along a fan-fold web, of a platen over which the web feeds in a tortuous course, said platen being 50 displaceable to straighten out the web, to permit the backward shifting of the carbons interleaved between the plies of the web, means for retaining stationary in the machine during the successive advances of the fan-fold web an additional work-sheet or web, to lie between the fan-fold web and the platen, to receive a condensed record of 55 the entries typed upon a succession of forms on the fan-fold web, and means at the delivery side of the platen for guiding said additional work-sheet clear of the fan-fold web.
- 55 32. The combination with means for shifting carbons backwardly, of a platen around which feed work-sheets interleaved with said carbons, means for displacing said platen to straighten out the sheets to permit the carbons to be shifted backwardly, and means for holding stationary one of the work-sheets 60 while other work-sheets are advanced, said holding means normally ineffective, but connected to be rendered automatically effective at the operation of displacing the platen.
- 60 33. The combination with a revoluble platen, of means to shift carbons backwardly, said platen being displaceable to permit the shifting of the carbons, a gage for the leading edges of certain of the work- 65
- 70 75 80 85 90 95 100 105 110 115 120 125 130

sheets intended to be fed simultaneously around said platen, and an additional gage for certain of the remaining work-sheets.

34. The combination of a revoluble platen, 5 a releasable clip for holding stationary a work-sheet upon the platen, and means for retracting a carbon relatively to the work-sheet held by said clip.

35. The combination of a revoluble platen, 10 a releasable clip for holding stationary one of the work-sheets upon the platen, said platen being displaceable to straighten out the work-sheets carried thereby, and means for retracting carbons while a work-sheet is 15 held stationary by said clip.

36. The combination of a revoluble platen, 20 said platen displaceable to straighten out the work-sheets carried thereby, a carbon-carrier shiftable to retract carbon sheets inter- 25 leaved between work-sheets carried by the platen, and a releasable clip for holding stationary one of the work-sheets while the others are being advanced and also while the carbons are being retracted; said carbon-carrier having means for carrying the carbon that is next to the clipped work-sheet.

37. In a typewriting machine, the combination with a revoluble platen and means at 30 the delivery side of the platen for severing a work-sheet or web carried around the platen, of means at the delivery side of the platen for diverting a record sheet arranged 35 between the remaining work-sheets and the platen, and means for holding said record sheet stationary while outer work-sheets are advanced thereover.

38. In a typewriting machine, the combination with a revoluble platen, of means 40 for displacing said platen bodily, a normally ineffective clip, and means associated with said platen-displacing means for rendering said clip effective to hold a work-sheet.

39. In a typewriting machine, the combination with a revoluble platen, of means 45 for moving said platen bodily to a position where some of the work-sheets carried thereon may be adjusted relatively thereto, and normally ineffective means for holding one 50 of said work-sheets while the others are being so adjusted.

40. In a typewriting machine, the combination with a displaceable platen, of a re-

leasable latch for said platen, and normally ineffective means for holding one of the 55 work-sheets on said platen while the others are being adjusted, said holding means being under the control of said releasable latch.

41. In a typewriting machine, the combination with a platen and a platen frame 60 therefor by which the platen may be moved to an abnormal position, of a releasable latch for said platen frame, and normally ineffective means for holding a work-sheet 65 to prevent its displacement relatively to the 70 platen when the latter is being moved to its abnormal position, said releasable latch being effective to render said holding means ineffective when the platen is returned to its normal position.

42. In a typewriting machine, the combination with a platen, of a carbon-carrier, means for shifting said carbon-carrier relatively to the work-sheet, and normally ineffective means for holding said work-sheet 75 when said carbon-carrier is being shifted.

43. In a typewriting machine, the combination with a platen, of a shiftable carrier having means to carry a plurality of carbons, means for displacing said platen 80 bodily to a position where some of the work-sheets thereon may be adjusted relatively thereto and where the carbons may be shifted relatively to said work-sheets, and normally ineffective means for clipping one 85 of said work-sheets when the platen is displaced, said clipping means being effective to hold said work-sheet to prevent its displacement when its associated carbon is being shifted relatively thereto.

44. The combination with a platen around which a work-sheet may be fed, of feed-rolls normally holding said work-sheet against said platen, means for changing the position of the work-sheet relatively to the 90 printing point, said feed-rolls being rendered ineffective during the changing of the position of said work-sheet, a clip for said work-sheet, and means for automatically rendering said clip effective to hold said 100 work-sheet before said feed-rolls are rendered ineffective.
